THORVALD MAIJGREN, OF ROCHESTER, NEW YORK, ASSIGNOR TO ELECTRO SURGICAL INSTRUMENT COMPANY, OF ROCHESTER, NEW YORK, A CORPORATION OF NEW YORK.

ELECTRIC COUPLING.

Application filed April 10, 1923. Serial No. 631,224.

My present invention relates to electrical connections and more particularly to couplings of the plug and socket type and it has for its object to provide an improved device 5 of this nature that will be simple in construction and convenient and serviceable in use. The improvements are directed in part to the provision of means whereby the coupling acts as a switch to make or break the circuit, 10 the two members being selectively interlocked in either of two positions in one of which the circuit is closed and in the other of which it is open. To these and other ends the invention resides in certain improve- 15 ments and combinations of parts all as will be hereinafter more fully described, the novel features being pointed out in the claims at the end of the specification.

In the drawings:

20 Figure 1 is a side view of a surgical appliance provided with a coupling constructed in accordance with and illustrating one embodiment of my invention;

25 Figure 2 is an enlarged side view of the coupling elements interlocked and in position to close the circuit;

Figure 3 is a longitudinal central section through the same;

30 Figure 4 is a view similar to Figure 2 with the members interlocked but in the position in which the circuit is open;

Figure 5 is a central section on Figure 4;

Figure 6 is a transverse section, further enlarged on the line 6—6 of Figure 2;

35 Figure 7 is a transverse section also further enlarged on the line 7—7 of Figure 4 and

Figure 8 is an end view of the socket member.

40 Similar reference numerals throughout the several views indicate the same parts.

In the present instance, I have illustrated my improvements embodied in a coupling by which surgical instruments are detachably connected to their lead wires. The instrument shown is a throat lamp but is of the general nature of various surgical instruments which comprise a stem 1 and having an electric lamp 2 at their outer ends requiring an electrical connection. The base 45 of the stem 1 constitutes a double contact plug 3 of the usual type, the central terminal at its lower end being shown at 4.

The socket, indicated generally at 5, embodies a cup 6 into which the lead wires 7

extend and into the top of which is threaded 55 a thimble 8, both of these parts being of insulating material as shown, preferably hard rubber. Within the thimble 8 is a central cavity 9 below which is a bushing 10 constituting a bearing for a yielding or a 60 reciprocating plunger contact 11 having an enlarged head 12 at its lower end movable in an enlarged portion 13 of the bushing to limit its upward or outward movement under the influence of a spring 14 surrounding 65 its upper end within the cavity 9 and acting against the bottom of the latter and against the shoulder 15 on the plunger.

The upper or plug receiving end of the 70 socket is constituted by three concentric sleeves 16, 17 and 18 the first two mentioned of which are formed as collar like extensions on the thimble 8 and are hence of insulating material, these being the outer and inner sleeves. The central sleeve 18 is a metallic 75 or conducting tube inserted between the other two. It constitutes one terminal of the socket having an extension 19 running down through the thimble 8 into the cup 6 and there joined to one of the lead wires 7. The other terminal is furnished by the plunger 11, the other lead wire being joined to the enlarged portion 13 of the bushing in contact therewith. It will be seen that the outer 80 insulating sleeve 17 is not absolutely essential 85 but is preferable to prevent short circuits.

The two inner sleeves 16 and 18 are cut away to form a longitudinal channel 20 to accommodate a laterally projecting interlocking pin 21 on the plug member 3 which 90 pin also constitutes the other terminal of the plug, the central terminal being indicated at 4 as aforesaid. Communicating with this longitudinal channel 20 is a slightly inclined lateral channel 22 that may extend through 95 all of the sleeves 16, 17 and 18 as shown in the form of a slot. On the upper surface of the side of such transverse channel there are formed two retaining notches 23 and 24 for the pin 21, the first mentioned being at the 100 end of the slot or channel and the other at an intermediate point. Following the insertion of the plug 3, a rotary movement thereof carries the pin 21 along the channel 22 and interlocks the two members, the pin being engaged in either the notch 23 or the notch 24. Meantime the terminal plunger 11 105 has been depressed upon the entrance of the

plug and is being held by its spring 14 against the terminal 4 of the latter.

As shown in Figure 3 the retaining notch 23 is formed in the terminal sleeve 18 of the 5 socket, the other sleeves being cut back so that contact of the pin 21 is there made only with this conducting sleeve and the circuit through the lamp 2 is closed. The other retaining notch 24, however, is in the same 10 manner formed in the sleeve 16, the terminal sleeve 18 being cut back as shown in Figure 5 so that engagement of the pin with this notch opens the circuit and the lamp 2 becomes inoperative. In both cases, nevertheless, 15 the plug and socket are effectively interlocked and thus, without detaching the instrument as is often convenient and without resorting to a separate switch usually provided at a more distant point, the circuit 20 can be conveniently controlled.

I claim as my invention:

1. An electric coupling embodying a socket member and a plug member receivable therein, the socket member having insulated and conducting portions and the plug member being provided with an interlocking projection that also constitutes one terminal thereof and which has two interlocking positions in one of which it engages 25 the conducting portion of the socket and in the other of which it engages a non-conducting portion and a contact yieldably mounted within the socket and adapted to engage the plug in all positions of the latter.

2. An electric coupling embodying a socket member and a plug member receivable therein, the socket member having insulated and conducting portions and being provided with intersecting longitudinal and transverse channels, and the plug member being provided with an interlocking projection that also constitutes one terminal thereof 30 movable in the channels and which has two interlocking positions in the transverse channel of the plug in one of which it engages

the conducting portion of the socket and in the other of which it engages a non-conducting portion thereof and a contact yieldably mounted within the socket adapted to engage the plug in both open and closed positions whereby said interlocking projection is constantly urged against the socket member within the transverse channel. 50

3. An electric coupling embodying a socket member and a plug member receivable therein, the socket member embodying insulating and conducting concentric sleeves and being provided with intersecting longitudinal and transverse channels and the plug member being provided with an interlocking projection that also constitutes one terminal thereof, said projection being movable in the channels into either of two interlocking positions in the transverse channel of the plug in one of which it engages the conducting 55 sleeve of the socket and in the other of which it engages the non-conducting sleeve and a contact slidably within the socket adapted to engage the plug in open and closed positions. 60

4. An electric coupling comprising a socket member including insulating and conducting telescoping sleeves provided with a transverse channel one side of which constitutes a bearing surface formed partially by each of the sleeves, a plug within the socket having a projecting contact portion disposed within the channel and movable in engagement with said bearing surface to and from open and closed positions through engagement and disengagement with the conducting and insulating sleeves, a contact member movable within the socket adapted to engage the plug in its open and closed positions, and means acting to urge said movable contact outwardly whereby to maintain said projecting contact portion in engagement with said bearing surface in all positions of the plug. 70 75 80 85
